LETTER HOLDER

Marion K. Summers, W. Commerce St.,
Brownstown, Ind. 47220

Filed June 22, 1970, Ser. No. 23,616

Term of patent 14 years

Int. Cl. D19—02

U.S. Cl. D74—9

FIG. 1

FIG. 2

FIG. 3

FIG. 4

FIG. 5

FIG. 6

FIG. 1 is a top plan view of a letter holder showing my new design;

FIG. 2 is a side view thereof;

FIG. 3 is an end view thereof;

FIG. 4 is a cross section taken on line 4—4 of FIG. 2;

FIG. 5 is a side view thereof, opposite to that of FIG. 2, and

FIG. 6 is a bottom view thereof.

The dominant feature of my design resides in the specific arrangement of the inserted discs in the sides of the letter holder as shown.

I claim:

The ornamental design for a letter holder, substantially as shown and described.
